UNITED STATES PATENT OFFICE.

WILLIAM R. ALLAN, OF PITTSTON, PENNSYLVANIA, ASSIGNOR TO HIMSELF AND WILLIAM L. WATSON, OF SAME PLACE.

WEATHER-STRIP.

SPECIFICATION forming part of Letters Patent No. 361,915, dated April 26, 1887.

Application filed January 26, 1887. Serial No. 225,547. (No model.)

To all whom it may concern:

Be it known that I, WILLIAM R. ALLAN, of Pittston, in the county of Luzerne and State of Pennsylvania, have invented new and Improved Weather-Strips, of which the following is a full, clear, and exact description.

My invention relates to an improved weather-strip, and has for its object to provide a device automatic in its action, which will fall noiselessly over the saddle as the door is closed, and effectively prevent the ingress of cold air or dust to a room.

The invention consists in the construction and combination of the several parts, as will be hereinafter fully set forth, and pointed out in the claims.

Reference is to be had to the accompanying drawings, forming a part of this specification, in which similar letters of reference indicate corresponding parts in all the figures.

Figure 1 is a longitudinal vertical section through a door-frame, with the casing and door partly broken away, illustrating in positive lines the application of my device upon an open door, and in dotted lines the position of the strip when the door is closed. Fig. 1^a is a detail view showing the arrangement of the clamp-strip on the opposite side of the door-frame. Fig. 2 is a transverse vertical section through the applied weather-strip, and Fig. 3 is a transverse section through a modified form thereof.

In carrying my invention into effect I attach transversely to the lower portion of the door A 35 a piece of molding, B, having a curve, b, under the outer edge, and drive a series of staples, C, in the lower edge of said molding centrally the same at intervals its length. I now provide a weather-strip, D, of wood or other 40 suitable or equivalent material constructed of a rectangular block, having its opposite corners, d d', rounded off, as shown in Fig. 2. Longitudinally of the top of the weather-strip D, from end to end thereof, I insert a continuous hinge, E, formed by bending a strip of metal upon itself and producing an eye, e, therein parallel with its curved side, the hinged connection with the molding B of the weather-strip D being effected by entering the staples 45 C through recesses cut in the curved edge of

the metallic hinge, and passing a rod, F, through the eye e and the said staples C. The curved lower edge of the molding B, projecting over the weather-strip D, constitutes a shed therefor and also a protection for the hinge. 55

In the lower outer edge of the weather-strip D, I insert a strip of rubber, G, the length of the weather-strip, adapted to effectually prevent the ingress of any cold air or dust, and diagonally the corner of the weather-strip next 60 the hinged side of the door, in the under edge, I journal a roller, H, for a purpose hereinafter described, as shown in dotted lines in Fig. 1 and positive lines in Fig. 2.

At the end of the saddle h, abutting the 65 casing to which the door is hung in the outer face, I produce a recess, h', and also a corresponding recess, h'', in the sill, forming a continuation of the recess h', as shown in dotted lines, Fig. 1. Thus, in operation, as the door 70 is closed the roller H travels upon the saddle, carrying the weather-strip noiselessly in advance of the door, and as said door latches the said roller drops into the recesses h' and h'', whereupon the convexed surface d of the 75 weather-strip fits in the concave surface of the saddle, forming a complete seal, the rubber strip G acting as an adjunct thereto.

I sometimes provide the outer surface of the weather-strip D with a metal facing, K, in 80 which event the said facing and hinge are made integral, as shown in Fig. 3, the metallic facing and hinge being held in position by entering the ends k k' of the metal strip in slots cut in the under edge and back of the 85 said weather-strip D.

As a means of retaining the weather-strip in close connection with the saddle when the door is closed, a clamp-strip, M, of wood or metal, is secured to the door-frame M' at the 90 base, the inner edge of the said clamp being of a contour adapted to receive and snugly fit when the door is closed the face of the weather-strip D and the molding B on which the weather-strip is hung. 95

This clamp effectually prevents the weather-strip from riding up out of contact with the edge of the saddle.

An ordinary weather-strip, N, may, if desired, be secured to the door-jamb, as shown 100

in Fig. 1, one end of which being made to rest upon the clamp M and the end carried upward against the top of the frame-casing.

Having thus fully described my invention, I claim as new and desire to secure by Letters Patent—

1. In a weather-strip for doors, the combination, with the molding B, having a curved under surface, b, and a series of staples centrally said under surface, of the weather-strip D, provided with an upper continuous longitudinal metal hinge, E, having a series of recesses in its upper curved portion, a lower longitudinal rubber strip, G, and a roller journaled transversely one end of said weather-strip, together with a rod, F, adapted to pass through the eye of said hinge E and engage the staples C, substantially as herein set forth.
- 15 2. In a weather-strip for doors, the combina-

tion, with the molding B, having a curved under surface, b, and a series of staples centrally said under surface, of the weather-strip D, having curved edges d d' and provided with an upper continuous longitudinal metal hinge, E, having a series of recesses in its upper curved portion, a lower longitudinal rubber strip, G, and a roller journaled transversely one end of said weather-strip, together with a rod, F, adapted to pass through the eye of said hinge E and engage the staples C, substantially as herein set forth.

WILLIAM R. ALLAN.
